WHIRLING SOUND DRUM TOY

Edmund J. Moddes and Louis Cinelli,
Kenosha, Wis.

Application August 4, 1940, Serial No. 351,406

1 Claim. (Cl. 46—52)

Our invention refers to toys, and it has for its primary object to provide a simple and effective sound-producing drum carrying any type of fibre string or runner, whereby the drum is rapidly whirled or rotated to produce a magnified sound effect incidental to its swirl.

With the above and other minor objects in view, the invention consists in certain peculiarities of construction and combination of parts, as will be hereinafter fully set forth in connection with the accompanying drawing and subsequently claimed.

In the drawing:

Figure 1 represents a perspective view of a sound box or drum embodying the features of my invention.

Figure 2 is a longitudinal, sectional view of one form of drum.

Figure 3 is a plan view of the same.

Figure 4 is a cross section of said drum, the section being indicated by line 4—4 of Figure 2.

Figure 5 is an inverted or bottom plan view of said drum.

Figure 6 is a fragmentary, perspective view of a whirling handle, with a looped strand or thread in position to be pushed over the finger tip.

Figure 7 is a sectional elevation of another form of my drum, whereby the same is constructed of light fibre material for cheapness in manufacture; and

Figure 8 is a top plan view of the same, with parts broken away and in section to illustrate structural features.

Referring particularly to Figures 1 to 6, inclusive, a drum 1 in this instance is shown constructed from any suitable material, such as wood, lignin-fibre, or any other suitable plastic composition. The drum 1 is hollowed out as indicated at X, and provided with a shoulder 2 for engagement with a thin disc 3, and the top of the drum is formed with a centrally disposed aperture 4. The bottom of the open or shell-like drum is sealed by a thin fibre head 5, which is provided with a plurality of perforations 6 therein, whereby the sound effect from the interior of the drum is developed.

The disc 3 is provided with companion perforations for threaded engagement of a double strand 7, and the companion strands are connected by a tie knot 8. These strands may be composed of any suitable material, such as horse hair, linen, or other fine fibre material, and, as shown in Figure 6 of the drawing, the upper end

of the double strand is looped to engage the grooved end of the whirling handle 9.

It will be noted that the type of drum shown in Figure 2 of the drawing is hollowed out in a series of conical steps, for the purpose of increasing the sound effect.

Referring particularly to Figures 7 and 8 of the drawing, the drum proper is made of paper pulp or other fibrous sheets rolled in cylindrical form, as indicated by the numeral 1'. The ends of the fibre drum have secured thereto a bottom head 10 and a top head 10', which heads are inwardly flanged to tightly engage the outer faces of the drum, to which said flanges are glued or otherwise permanently secured. To further facilitate rigidity of the drum, a paper jacket 11 encases the drum shell and flange heads, to which it is cemented or otherwise secured, and this jacket may be used for ornamental designs or an advertising feature.

The upper head 10' of the drum is provided with companion apertures through which the pair of fibre or horse hair strands 7—7 extend, and are secured at the lower face of the head by a knot 8'; it being understood that the upper loop 7' encircles the groove in the dowel or handle 9, whereby the toy is manipulated.

In view of the fact that the paper fibre drum, as shown in Figures 7 and 8, may be light in weight, the said drum has seated therein between its head a volume of loose material 12 of sand or other substance, whereby the drum is given sufficient weight to facilitate the whirling effect imparted thereto by the finger and fibre strands.

From the foregoing description, it is understood that we may construct the toy from any suitable material, the essential features being the hollow drum, with finger means and fibre strands connecting the finger means to the drum whereby it is whirled or rotated. Thus, due to rotation, the sound vibrations will be magnified because of the hollow drum structure, including the heads.

While we have shown and described two exemplifications of my invention, it is understood that we may vary the structural features within the scope of the claim.

It will be noted that in order to facilitate sound effects, the outer end of the dowel or handle is saturated in oil, especially the groove.

We claim:

A sound toy comprising a cored drum, the core comprising a plurality of cylinders decreasing in area from the bottom to the top of said drum, each cylindrical portion being intersected

by an abrupt transverse shoulder, the uppermost cylinder being provided with a vent aperture, a perforated fibre head secured to the bottom of the drum, a thin vibratory disc secured to the shoulder of the bottom cylindrical core portion, whereby a single sound chamber is developed at the bottom of the drum to emit sound impulses, and a plurality of gradually

diminishing sound chambers are developed above the disc, to emit sound impulses through the vent aperture, and a whirling strand secured to said disc extending through the drum vent aperture.

EDMUND J. MODDES.
LOUIS CINELLI.
